UNITED STATES PATENT OFFICE.

BROOKE ANDERSON, OF CHICAGO, ILLINOIS.

FENCE-POST.

1,234,113.

Specification of Letters Patent. Patented July 24, 1917.

Application filed February 21, 1916. Serial No. 79,528.

To all whom it may concern:

Be it known that I, BROOKE ANDERSON, a citizen of the United States, residing at Chicago, in the county of Cook and State 5 of Illinois, have invented certain new and useful Improvements in Fence-Posts, of which the following is a specification.

This invention relates especially to metallic fence posts and has for its object the provision of a post which shall more 10 efficiently secure the fencing attached to it against the strains to which it is subjected, which shall be more easily handled in the erection of fencing and which shall be 15 cheaper in construction and more efficient in operation than posts heretofore made. Other objects of the invention will appear as the device is described more in detail.

The invention is exemplified in the combination and arrangement of parts shown 20 in the accompanying drawing and described in the following specification and it is more particularly pointed out in the appended claims.

25 In the accompanying drawing,—

Figure 1 is an elevational view of one form of fence post embodying the present invention.

Fig. 2 is a horizontal section on line 2—2 30 of Fig. 1.

Fig. 3 is an elevation of a modified form of the invention.

Fig. 4 is a horizontal section on line 4—4 35 of Fig. 3.

Figs. 5, 6 and 7 are fragmentary sectional views showing in detail the method of securing fencing to the post.

Fig. 8 is a perspective; and,

Fig. 9 is a side elevation of an especially 40 designed staple used for securing fencing to the post.

In the erection of wire fencing where 45 wood or concrete posts are used a great amount of exhaustive labor is necessary for the digging of holes in which the posts are set. In the present invention steel posts are used, the cross-diagonal area of which is so small that the post can be driven into the ground without the necessity of previously digging a hole. Where posts of this 50 kind are used however, the lateral area of the post proper supported by the ground is not sufficient to resist the strains to which the fence may be subjected. It is, therefore, 55 necessary to provide additional anchorage devices to sustain the post against lateral

strain. In posts of this general character previously constructed, difficulty has been experienced in locating the anchorage device relative to the post itself and to the attaching means for the fence so that the strain upon the fence wire would be properly balanced and overcome by the anchor and yet leave the attaching devices properly located on the post to permit the fence to be secured thereto in the most convenient manner. In the present invention the applicant has arranged the anchoring device and the attaching means symmetrically relative to the longitudinal axis of one of the lateral 60 faces of the post thus balancing the anchor against the strains to which the post is subjected and yet providing for the attachment of the fencing to a flat web of the post to which it may be most easily secured when 65 the especial attaching means embodying a part of this invention is used for that purpose.

Referring first to Figs. 1 and 2 of the drawing, the numeral 10 designates generally a fence post composed in this instance of an angle iron having two webs 11 and 12 at right angles to one another. Both of the webs are beveled off as shown at 13 to provide a sharpened point for the post 70 to permit the same to be easily driven into the ground. The web 11 is provided with a series of holes 14 which are drilled or punched through the web along the longitudinal axis thereof. The fence wire 15 75 constituting the fencing supported by the post is secured to the post by means of the holes 14, in the manner illustrated in Figs. 5, 6 and 7 and which will be later explained. To hold the post from twisting in the 80 ground and to withstand lateral strains to which it is subjected, an anchor plate 16 is secured to the post in a position spaced a short distance from the lower end thereof, but located a considerable distance below 85 the ground line. This plate is preferably triangular in shape with its pointed end 17 directed downwardly and the plate itself is so located relative to the web 11 of the post that the lateral surfaces thereof are equally 90 distributed on opposite sides of the longitudinal axis of the web 11. This brings the central axis of the anchor plate 16 in position to coincide with the axis of the web 11, thus properly locating the anchor 95 relative to the strain imposed upon the post and the fencing attached thereto to prevent 100 105 110

twisting of the post in the ground and to prevent movement of the post laterally relative to the fence line. Where the especial attaching device illustrated in the drawing 5 is used in securing the fencing to the post, this arrangement of the anchor 16 is permissible since it is not necessary where this attaching device is used to provide against strains longitudinally of the fence line. The 10 reason for this will be apparent when the especial attaching device is explained.

Figs. 3 and 4 illustrate a slightly modified form of the invention, the post in this case being made of T-iron instead of angle iron. 15 In this form of invention the fencing is secured to the web 18 which forms the head of the T and the holes 19 in which the fastening devices are secured may be spaced in any suitable manner on opposite sides of the web 20 20 which constitutes the stem of the T. An anchor plate 21 is provided which is in all respects similar to anchor plate 16 and which is secured to the web 18 in a position symmetrically with respect to the longitudinal 25 axis of the web. In connection with Figs. 3 and 4 a circular disk 22 is shown having a central opening 23 therein arranged to slide freely over the body of the post, as illustrated in Fig. 4. While this disk is shown in connection 30 with the form of post illustrated in Fig. 3, it should be understood that it can be used in connection with either form of the post whenever conditions make it necessary. The object of the disk 22 is to counteract upward strain on the post and it is used where the fence dips into hollow places or where for any other reason the post is subjected to an upward strain. In the setting of posts to which the disk 22 is applied, it is necessary 35 to dig a hole in the ground equal to the diameter of the disk for a portion of the depth to which the post is sunk. The post is then driven into the center of the hole so dug until the top of the anchor plate 16 40 or 21 reaches the bottom of the hole provided. The plate 22 is then placed over the post and allowed to drop until it rests on the top of the anchor plate 21 and the bottom of the hole provided. The earth is then filled into 45 the hole and tamped in place, thus causing the plate 22 to form an anchor resisting any upward strain on the post.

When a post has been installed either with or without the anchor plate 22, it will be noted 50 that the post will be held firmly from lateral strain at a point considerably below the ground line. The earth above the anchor plate forms a somewhat yielding cushion resisting lateral strain upon the post and in this way bending of the post at the ground line is prevented.

The fencing is attached to the posts by especially designed staples which may be made upon the ordinary stapling machines 55 by especially arranged dies and which are

driven into the holes provided in the posts in the usual manner of driving staples, the act of driving the staple being sufficient to clench the staple in the post. As shown in Fig. 5 the shank 23 of the staple is bent somewhat inwardly toward the shank 24 so that the points of the staple are spaced from one another a distance considerably less than the diameter of the curve formed by the outer portion of the wire at the head of the staple. 70 As illustrated in Figs. 5 and 6, the opening 19 into which the staple is driven is of less dimension than the width of the head of the staple, so that when the staple is driven into the opening the points are gradually bent inwardly toward one another until they cross one another, as shown in Fig. 6 thus firmly securing the staple to the post. The staple of course is first placed astride one of the strands 15 of the fencing and in this way the fencing is secured to the post against movement transversely of the fence line, but is free to slide relative to the post longitudinally of the line of the fence. Because of this arrangement, no strain is brought upon the post in the direction of the fence line and it is therefore not necessary to anchor the post especially against strain in this direction. This is the reason that the anchor plates 16 and 21 may be positioned directly in a plane parallel with the fence line. The openings through which the staples are driven may be either oblong as shown at 19 in Figs. 3, 5 and 6 or circular as shown at 14 in Figs. 1 and 7, the result in either case would be substantially the same. In order that the inturned shanks of the staples may not strike one another when the staple is driven into the post, but may freely pass to form a proper anchorage, the shank 23 is not only bent inwardly toward the shank 24, as shown in Fig. 15, but it is also bent laterally relative to the plane of the staple, as shown in Fig. 9. This gives the shank 23 a compound curve, as illustrated in the perspective shown in Fig. 8. It should be noted that the shank 24 of the staple is not bent, but is left straight as is the case in staples of the ordinary form used for being driven into wood. This is a very important feature 100 in the manufacture of the staples since it is possible to make a staple having one straight shank and one curved shank on the ordinary staple forming machines simply by properly adjusting the dies. It is impossible however 105 to do this where it is attempted to curve both shanks of the staple. By curving one instead of both shanks, the ease of manufacture of the staple is very much increased and consequently the cost of the staple is correspondingly diminished.

Having thus described my invention, what I claim as new and desire to secure by Letters Patent of the United States is:

1. In combination a fence post comprising 130

5 a metallic web member having an opening therein, and a device for securing fencing to said post comprising a staple having one straight shank and having the point of its other shank bent inwardly toward the point of said straight shank and also bent laterally relative to the strain of said staple whereby the shanks of said staple when driven into the opening of said web member will be 10 caused to cross one another to anchor said staple in said post.

15 2. In combination a metallic fence post having a web member provided with an opening therein, means for securing fencing to said post comprising a staple having the shanks thereof spaced apart at the head of said staple a distance greater than the diameter of said opening and having the point of one of said shanks bent inwardly toward the other of said shanks an amount sufficient to bring said points near enough to one another to enter the opening in said web member, said inwardly bent point being also bent laterally relative to the plane of said staple 20 whereby said shanks when driven into said opening will cross one another to firmly anchor said staple in said opening and to hold a fence wire placed between said shanks from transverse movement relative to said post, but to permit said wire to move longitudinally through said staple relative to said post.

25 3. A staple for securing fence wire having one straight shank and one curved shank, said curved shank being bent inwardly toward said straight shank and also being bent laterally relative to the plane of said staple.

30 4. In combination a fence post comprising an angle iron having two web members arranged at an angle to one another, means for

securing fencing against the flat face of one of said web members, a triangular anchor plate secured to said web member and having the pointed end thereof directed downwardly and one edge of said triangular plate 45 extending in a horizontal direction, and a second anchor plate having an opening therein arranged to fit over said post to permit said plate to rest upon the edge of said triangular anchor plate which extends in a horizontal direction. 50

5. In combination a fence post comprising an angle iron having web members extending longitudinally thereof and arranged at an angle to one another, a series of openings in 55 one of said web members arranged symmetrically relative to the longitudinal axis thereof, means coöperating with said openings to secure fencing to said web member in a manner to permit longitudinal movement 60 of said fencing relative to said post, a triangular anchor plate secured to said web member below the ground line of said post with its pointed end extending downwardly and with the upper edge thereof lying in a 65 horizontal direction, the lateral faces of said plate extending equally on opposite sides of the longitudinal axis of said web member, and a second anchor plate having an opening therein arranged to fit over said post to 70 permit said plate to rest upon the horizontal upper edge of said triangular plate.

In testimony whereof I have signed my name to this specification, in the presence of two subscribing witnesses, on this 17th day of 75 February, A. D. 1916.

BROOKE ANDERSON.
